PHASE-SHIFT CIRCUIT FOR GRID-CONTROLLED GAS DISCHARGE TUBES

John Harold Lucas, Salfords, near Redhill, England, assignor to Hartford National Bank and Trust Company, Hartford, Conn., as trustee

Application March 30, 1950, Serial No. 152,829
In Great Britain May 20, 1949

2 Claims. (Cl. 315—194)

1

The invention relates to phase shifting circuits employing direct current saturable reactors for the grid control of two or more electric discharge tubes.

It is known to use such circuits so that at desired instants at which conduction is to ensue rapid changes occur in the voltage which is applied to the grid or grids of the discharge tubes. This is a desirable characteristic for the control of electric discharge tubes having a gas of vapour filling, more especially when they are used in rectifier circuits or to supply an inductive load. In such circuits stable working may depend on the steepness of the grid control voltage waveform during the said rapid changes.

The circuit diagram shown in Figure 1 of the accompanying drawings, shows simply, a known phase shifting circuit of the type referred to. A transformer 1 has its primary winding 2 supplied from a source of alternating voltage 3, while its secondary winding 4 is centre-tapped at 5. The voltage across winding 4 is applied across the series connection of one winding 6 of a transformer 7 and a resistance 8 having their junction at 9. A transformer 7 has a core capable of magnetic saturation by a winding 10 which is supplied from a source of direct current 11, preferably through an inductance 12 (or a high resistance) so as to keep out alternating current from the circuit comprised by winding 10, inductance 12 and the source 11.

The alternating voltage E_g that appears between points 5 and 9 will have a certain phase relationship to that of the source 3, and it is well known that this phase may be shifted in angular degrees over a range of nearly 180° by varying the saturation of the core of transformer 7 by means of the source 11. An accompanying effect is that the wave-form of the voltage E_g is distorted with reference to the waveform of the source 3 due to non-linearity of the magnetic core 7, and if this core is of a material having a high permeability and a sharply defined saturation flux density, such as the material having the registered trade-mark "Numetal," the waveform of the voltage E_g may be arranged to exhibit rapid changes which are nearly discontinuous.

When only one discharge tube has to be controlled it is achieved simply by connecting the cathode to point 5 and the grid to point 9 and arranging that the rapid change of voltage is such as to drive the grid positive at the desired instant of conduction. This instant may be varied

2

simply by varying the direct current supplied to winding 10.

When two discharge tubes have to be controlled which are operated in bi-phase, it has hitherto been usual to obtain a voltage E_g across points 5 and 9 which is applied to the primary of a transformer having a centre tapped secondary winding the centre tap being joined to the cathodes of the discharge tubes, one end of the secondary winding joined to the control grid of one tube, the other end being joined to the control grid of the other tube. Apart from the transformer 1, it has therefore been necessary to use one transformer to obtain variable phase shift and another transformer to allow bi-phase operation and the design of these two transformers is such that they have generally been different in type.

The present invention seeks to obtain an equivalent result by using a circuit employing a plurality of identical transformers of the type of transformer 1 in Figure 1, having the direct current windings so connected as substantially to balance out the alternating currents generated in them. The impedance in series with the D. C. source may then be of much reduced value or may be eliminated.

According to the present invention, a phase-shifting circuit for the grid control of discharge tubes operating in multi-phase relationship on a multi-phase alternating current supply, has a saturable reactor connected in series with a resistance across each phase of the supply, the junction between the saturable reactor and the resistance of each pair being connected to supply a grid control potential to the corresponding discharge tube and each of the saturable reactors has a direct current winding for saturating the core of the reactor, connected in series across a variable direct current supply.

A phase-shifting circuit, according to the invention, for the grid control of two discharge tubes connected for bi-phase operation on an alternating current supply, has a bridge-connected network consisting of two saturable reactors in two opposite arms of the bridge and two resistances in the two adjacent opposite arms, two opposite points of the bridge network being connected across the alternating current supply and the other two opposite points of the bridge network being connected each to supply a grid control potential to the corresponding discharge tube and both the saturable reactors having a direct current winding for saturating the core of the reactor connected in series across the variable direct current supply.

An impedance, preferably, a choke, may be connected in series with the direct current windings of the saturable reactors and the variable direct current supply, in either of the arrangements described above.

One circuit according to the present invention, employing two discharge tubes connected for bi-phase operation on an alternating current supply, will now be described by way of example, with reference to Figure 2 of the accompanying drawings.

In Figure 2, corresponding reference numerals to those used in Figure 1 are used to denote the corresponding function of parts described in Figure 2.

Two grid-controlled discharge tubes 13 and 13' are connected for bi-phase operation from the alternating current supply 3, having their anodes connected to opposite ends of a centre-tapped secondary winding 14 of a transformer 1, whose primary winding 2 is connected across the alternating current supply 3.

A bridge-connected network consists of two saturable reactors 7 and 7' having their reactive windings 6 and 6' connected in two opposite arms of the bridge network. Two resistances 8 and 8' are connected in the two adjacent opposite arms. Two opposite points 9 and 9' of the bridge network are connected to supply grid control potentials to the two discharge tubes 13 and 13'. The point 9 is connected through a grid resistance 15 to the grid of the corresponding tube 13, that is, the tube whose anode potential is in the required phase relationship to the potential appearing at point 9. The point 9' is connected to the grid of the corresponding discharge tube 13' through a grid resistance 15'. The other two opposite points in the bridge network are connected to the outer ends of the centre-tapped winding 4 of transformer 1, the centre point 5 being connected to the cathodes of the two tubes 13 and 13'.

The direct current windings 10 and 10' of the saturable reactors 7 and 7' are connected in series with each other and in series with a choke 12 across a variable direct current supply 11.

As with the circuit of Figure 1, the control of the discharge tubes in Figure 2 is effected by varying the magnitude of the current flowing through the direct current windings 10 and 10' of the saturable reactors 7 and 7'. The phase change of the potential at the points 9 and 9' varies correspondingly in relation to the anode potential of the corresponding valve so that the variation of the direct current supply 11 controls the two tubes 13 and 13' in a similar manner.

Since the direct current windings 10 and 10'

are connected in series, the alternating potential induced in each of them cancels out approximately so that only a very small alternating potential appears across the variable direct current supply 11. Any residual potential is suppressed by the inclusion of the choke 12 described in connection with this example. In this case, the choke 12 need have only a much smaller impedance than the choke 12 in Figure 1 and may be eliminated altogether if the direct current supply 11 has a sufficiently high internal impedance.

The advantage of the circuit shown in Figure 2 is that the transformers 7 are simple two winding types, identical in construction while, due to the direct connection of the grids to the phase shifting elements, there is not the load on these elements that would occur if a phase transformer were interposed. The waveform of the grid voltage has the same desirable properties as that obtained from the circuit shown in Figure 1.

What I claim is:

1. Phase-shifting apparatus for the control of two grid-controlled discharge tubes connected in a two phase circuit to an alternating current supply, said apparatus comprising a pair of saturable reactors having a direct-current winding, the direct-current windings of said reactors being connected in series, a pair of resistances, a four arm bridge network, one pair of opposing arms of said network being constituted by said reactors, the other pair of opposing arms being constituted by said resistances, means to apply a variable direct-current to said serially connected windings, said windings being connected serially in a direction at which the alternating currents induced therein by said reactors are substantially balanced out, means connecting one pair of vertices of said bridge network to said alternating-current supply, and means connected to the other pair of vertices to the control grids of said tubes.

2. Apparatus, as set forth in claim 1, further including an impedance in the path of said variable direct-current.

JOHN HAROLD LUCAS.
